UNITED STATES PATENT OFFICE

131,407

DESIGN FOR A COMBINATION KNIFE BLADE AND FILE

Howard L. Fischer, St. Paul, Minn.

Application May 1, 1941, Serial No. 100,734

Term of patent 14 years

To all whom it may concern:

Be it known that I, Howard L. Fischer, a citizen of the United States, residing at St. Paul, county of Ramsey, and State of Minnesota, have invented a new, original, and ornamental Design for a Combination Knife Blade and File, of which the following is a specification, reference being had to the accompanying drawing, forming part thereof.

I claim:

The ornamental design for a combination knife blade and file, as shown.

HOWARD L. FISCHER.
